[57] CLAIM

The ornamental design for a motorcycle luggage rack, substantially as shown and described.

DESCRIPTION

FIG. 1 is a front elevational view of a motorcycle luggage rack showing our new design;
FIG. 2 is a rear elevational view thereof;
FIG. 3 is a top plan view thereof;
FIG. 4 is a bottom plan view thereof; and
FIG. 5 is a left side elevational view thereof, the right side being a mirror image of that shown.

FIG.1

FIG.2

FIG.3

FIG.4
